UNITED STATES PATENT OFFICE.

HUGO JUNKERS, OF DESSAU, GERMANY.

RIVETING DEVICE.

Application filed June 28, 1920. Serial No. 392,593.

To all whom it may concern:

Be it known that I, HUGO JUNKERS, a citizen of the German Empire, residing at Dessau, Germany, have invented certain new and useful Improvements in Riveting Devices (for which I have filed application in Germany, dated Oct 1, 1918), of which the following is a specification.

My invention relates to riveting devices and more especially to a device for riveting long hollow work pieces such as tubes and the like. Up till now the riveting of such work pieces, especially such of small cross-sectional dimensions, was very difficult and wearisome inasmuch as fetching each single rivet, introducing same in the rivet hole, holding it during the riveting operation and so on required numerous wearisome manual operations. By introducing the rivet from outside and forming the closing head from inside the work piece a considerable loss of time was added to the unreliability characterizing the internal riveting.

There are other devices, in which the tube to be riveted is placed over a stationary mandrel, the rivets being advanced to the riveting point within this mandrel and there introduced into the rivet hole by means of a lifting device, whereupon the forming 30 of the closing head is effected from the outside. However in order to be able to use such machines the work piece must allow of being easily shifted on the mandrel whereas they are useless in those cases, where the work piece cannot be displaced with ease as is the case for instance in the construction 35 of large frames, composed of tubular elements or in covering or lining such frames with sheet metal. The riveting device according to the present invention allows to introduce into the work piece, no matter whether it can be easily handled or not, a greater number of rivets at a time, said rivets being then inserted, one after the other, 40 in the respective rivet holes. To this end the novel riveting device is constructed substantially as follows: A body whose cross section is adapted to the free cross section of the work piece, and which can be freely moved within the latter, receives a greater 45 number of stored rivets in a sort of magazine. The said body further carries devices for advancing the rivets, for inserting them in the rivet holes and for carrying an abutment or anvil underneath the rivet insert-

ed in the hole, this being effected by means of a long rod or sleeve suitably guided within a collar or socket at the end of the work piece and which can be adjusted and fixed if required. In order to permit the devices 50 provided within the body for advancing the rivets, for inserting the same in the rivet holes, for adjusting the riveting abutment and the like to be easily operated from the outside, they are moved by means of longitudinally movable or rotatable transmitting members, which can be operated from the free end of the sleeve carrying the body. With the sleeve serving for shifting the riveting device arrangements are preferably 60 connected which serve for carrying and adjusting the rivet exactly below the appropriate rivet hole in order to facilitate the accelerate the insertion of the rivets.

Further details of the invention may be 70 guessed from the following description and from the drawings affixed thereto and forming part thereof, wherein several embodiments of my invention are illustrated.

In the drawings—

Fig. 1 is a longitudinal section of the riveting device and the work piece, in which it is inserted,

Fig. 2 a plan view of the riveting device shown in Fig. 1.

Fig. 3 is a cross-section on the line III—III in Fig. 4 and

Fig. 4 a partial section drawn to an enlarged scale of the whole device, the anvil with a rivet resting thereupon being 90 shown in inoperative position,

Fig. 5 shows the same parts in operative position,

Figs. 6 and 7 are a plan and section respectively of a detail and

Fig. 8 is a section of another form of construction of the sleeve illustrated in Fig. 1.

Referring to the drawings, 2 is a collar or socket clamped upon the end portion 100 of the work piece 1 by means of a screw or screws 3. In a bore of the socket 2 a rotatable body 4 is slidably arranged, said body being provided with a slot 5. A pin 6 mounted in the socket 2 and projecting 105 into said slot permits only a longitudinal movement of the body 4 for the length of said slot. Within the body 4 there is provided a sleeve 7 which can be shifted in a longitudinal direction independently of 110

said body, but which can also be rigidly fixed to the body 4 by means of flanges 8 and screws (not shown), whereby the body 4 and the sleeve 7 can be moved only in 5 common in a longitudinal direction, rotation being prevented altogether by the pin 6. In longitudinally displacing the sleeve 7 the member 9 rigidly connected to the sleeve 7 for instance by screws, is displaced 10 as well. The flattened upper portion of member 9 carries a guide 10 adapted to receive a greater number of rivets. The member 9 is cut out rectangularly at its free end so as to make room for a wedge 11. It is further provided in its upper portion with a notch allowing the insertion of a fork-shaped part 12, embracing the wedge 11. A plate 13 inserted along with the part 12 or immediately thereafter and a 15 leaf spring 14 secured to said plate, are attached to the member 9 by means of the rivet guide or magazine 10, placed upon the body 9 after plate 13 with leaf spring 14 have been inserted. A threaded bolt 20 15, is screwed into the wedge 11, said bolt being surrounded by the sleeve 7 and connected therewith in such a manner, that it can be rotated independently thereof by means of a crank 16 and a flange 16' rigidly connected thereto. On the other hand 25 however the crank and the bolt respectively being moved axially will cause to take place a longitudinal movement of the sleeve 7 and the body 9 secured thereto. On the 30 crank being rotated the wedge 11 too will move in a longitudinal direction, this movement being limited in the one sense by a plate 9', secured to the body 9, while a movement of wedge 11 in the other sense will 35 result in part 12 and a lever 17 being raised. Lever 17 being pivotally mounted on a pin 40 18 on part 12 is oscillated by striking the inner wall of the work piece. On lever 17 being oscillated it withdraws from the anvil 21 a leaf spring 20 with bifurcated ends 45 and thereby releases the rivet embraced by said spring.

The operation of this device is as follows: The member 9 having been introduced in 50 the interior of the work piece the socket 2 is clamped to the end of the latter. Thereupon a pin (not shown in the drawing) is inserted in a rivet hole and at the same time the member 9 is shifted in the direction of the longitudinal axis by means of 55 the sleeve 7 and the bolt 15 and crank 17 respectively, until said pin meets with the hole 22 of the member 9. For the purpose of facilitating this the member is cut out 60 on its upper surface in the manner indicated in the drawing. By means of a rod 23, passing through a bore of the socket, pressure is now exerted on the row of rivets, arranged in the rivet guide or magazine and 65 the foremost rivet is thus shifted on to the

anvil 21, where it is guided by the spring 20, holding the rivet shank in its bifurcated end and pressing its head down upon the anvil. In order to transport the rivet underneath the rivet hole, into which it is 70 to be inserted, the body 4 is moved into the position shown in Fig. 1 and is thereupon rigidly clamped to the sleeve 7 in the manner before described. Now the pin is removed from the hole 22 and the whole device—with the exception of the socket 2, which remains clamped to the work piece—is shifted towards the left, until the solid portion of the body 4 at the end of slot 5 strikes the pin 6. As the length of the 80 slot 5, after deducting the diameter of the pin, corresponds exactly to the distance between the center of the hole 22 and the axis of the rivet, the rivet resting on the anvil now stands exactly below the rivet hole into which it is to be inserted. By turning the crank 16 and thereby bolt 15 a little a longitudinal displacement of the wedge 11 is effected. In consequence thereof the member 12 and the rivet on the 85 anvil are lifted and the rivet is inserted in the hole. The lever 17 pivotally mounted on the member 12 abuts against the inner wall of the work piece and by oscillating causes the spring 20 to oscillate also 90 and thereby to release the rivet. At this moment the rivet is totally inserted in the rivet hole and its head is pressed flat against the inner wall of the work piece, so that the riveting can now be proceeded with as 95 usual. After this has been accomplished the crank is turned backwards and in consequence thereof the wedge is returned into its initial position. The member 12 is caused to drop down by its own weight and 100 by the pressure of the spring 14, secured to the plate 13, this latter being detachably connected to the member 9 in order to allow the insertion of the part 12. The lever 17 returns to its normal position under the influence of the spring 19 and the leaf spring 20 again rests with its bifurcated end on the anvil. The whole operation is gone through again until all the rivets contained in the magazine have been disposed of. 11

As may be seen from the foregoing description, the safe insertion of the rivets in the rivet holes is insured independently of whether the distances between any two rivet holes are equal or not.

In the case of work pieces having their rivet holes equally distanced apart the sleeve 7 may be provided, according to Fig. 8, with holes 24, whose distance exactly corresponds to the distance between the rivet holes. Pin 6' projects through the slot into these holes. In this case it is no more necessary to first carry the hole 22 and then the rivet itself below the rivet hole, but after a rivet has been riveted, the sleeve 7' is merely ad- 125 130

vanced, until the pin 6' catches in the next following hole 24. Now a fresh rivet is underneath the appropriate rivet hole.

Obviously the device can be employed for 5 hollow work pieces of any desired length, it being only necessary to employ a bolt 15, sleeve 7 and rod 23 of sufficient length. The workpiece may be of any section, it being only necessary to adapt thereto the form of 10 the member 9.

I wish it to be understood that I do not desire to be limited to the exact details of construction shown and described, for obvious modifications will occur to a person 15 skilled in the art.

I claim:

1. In a device of the kind described in combination an abutment, adapted to be inserted in a hollow body, means for carrying 20 said abutment opposite a predetermined point of the inner wall of said body and means for moving said abutment in the direction towards said point.

2. In a device of the kind described in 25 combination an abutment adapted to be inserted in a hollow body, a wedge underneath said abutment, means for carrying said abutment and said wedge opposite a predetermined point of the inner wall of said body 30 and means for moving said wedge so as to cause said abutment to move in a direction towards said point.

3. In a device of the kind described in combination an abutment, adapted to be inserted in a hollow body, a rivet magazine 35 near said abutment, means for carrying a plurality of rivets in succession from said magazine to said abutment, a wedge adapted to be reciprocated relatively to and to lift 40 said abutment and means for displacing said abutment, said wedge and said magazine

within said body the exact distance between two consecutive rivet holes.

4. In a device of the kind described in 45 combination, an abutment adapted to be inserted in a tube, means projecting from said tube for axially displacing said abutment, means for limiting said displacement to the distance between two consecutive rivet holes and means adapted to be operated from outside for moving said abutment in the direction towards a rivet hole. 50

5. In a device of the kind described in 55 combination, a body of a cross section approaching that of the tube to be riveted, an abutment movable within an indenture of said body, means adapted to be operated from outside for axially displacing said body and abutment within said tube, means for limiting said axial displacement to the 60 distance between two consecutive rivet holes and means for displacing said abutment transversely of said body.

6. In a device of the kind described in 65 combination, a body of a cross-section approaching that of the tube to be riveted, an abutment movable within an indenture of said body, means adapted to be operated from outside for axially displacing said body and abutment within said tube, means for limiting said axial displacement to the 70 distance between two consecutive rivet holes, means for displacing said abutment transversal of said body, a rivet magazine, means for feeding rivets from said magazine in 75 succession on to said abutment, means for holding a rivet on said abutment and a lever adapted to withdraw said holding means, as said abutment is displaced transversal. 80

In testimony whereof I affix my signature.
HUGO JUNKERS.
